UNITED STATES PATENT OFFICE.

CHRISTIAN RUMOHR, OF NEW YORK, N. Y.

AEROPLANE TOY.

Application filed October 20, 1921. Serial No. 508,911.

To all whom it may concern:

Be it known that I, CHRISTIAN RUMOHR, a citizen of the United States, and resident of New York, in the county of New York and State of New York, have invented certain new and useful Improvements in Aeroplane Toys, of which the following is a specification.

The object of this invention is to provide 10 a toy having a more or less extended wing surface so constructed and arranged that it may be caused to rise upwardly to simulate flying without the necessity of providing any spring or other motors, the upward 15 flight of the toy being caused solely by a moving current of air.

Another object is to provide a means to regulate the upward flight of the toy, when desired, to compensate for the stronger lift- 20 ing force due to greater velocities of the air current.

With these and other objects in view that will be in part obvious and will appear more in detail hereafter, the invention consists 25 in the following combinations of parts, reference being had to the following specification and the accompanying drawing, forming a part thereof in which a preferred embodiment of my invention is 30 shown and in which—

Figure 1 is a side elevation of the device shown as attached to the radiator cap of an automobile.

Figure 2 is a plan view of the structure shown in Figure 1 with a part shown in section.

Figure 3 is a section of the front part of the device taken along the line $\alpha-\alpha$ of Fig. 2.

Figure 4 is a section along the same section line of the tail end of the machine.

As shown in the drawing a vertical rod 6 is suitably secured to the cap 5 of an automobile radiator though it will be understood 45 that the rod may be secured to any movable object. The toy may be made in the form of an aeroplane as shown in the drawing which comprises the body portion 7 which may be secured by a pair of collars 50 13 upon a sleeve 8 adapted to slidably embrace the rod 6 and guide the toy along the rod, and when made as an aeroplane a propeller 9 is provided. The wings 10 and 11 of the aeroplane are provided with holes 12 to aid the collar 8 in guiding the toy along the rod which holes may be just large

enough to permit the toy to slide freely along the rod or which may as shown in the drawing, be larger than the holes 12 in the collar 8 to allow the toy to have a limited oscillating movement to give a careening motion to the toy during its raising or lowering motion along the rod, in the latter case, that is when it is desired to have the aeroplane move with a careening movement, 65 a slight play is provided between the collars 13.

The rear end of the toy is preferably provided with a rudder 14 which serves to keep the front or head of the toy into the wind. A tail 15 is provided with a slot 16 just wide enough to frictionally engage the sides of the rudder but to allow the tail to be moved relatively to the rudder. Passing through the tail adjacent to one side of the rudder is a rod 17 suitably secured to the rudder and provided on its upper and lower ends with eyes or other suitable means to which may be secured a pair of strings 19 and 20. Along the front of the body at any suitable point, a series of suitable fastening devices 21 may be provided to which the ends of the lines 19 and 20 may be secured to hold the rudder securely in adjusted position.

It will be understood that the toy may be made in any desirable shape or form to simulate as for example a bird or other object as well as an aeroplane, and it will also be understood that the rod may be secured upon the roof of a building or may be extended between the ground and the upper stories of a building or in any other suitable place, in which case the rod may be of quite considerable length and in the presence of a breeze of sufficient velocity the extent of the upward flight of the toy will only be limited by the length of the rod. I have found that when attached to an automobile as shown in the drawing that with the tail set in the lowermost or full line position shown in Fig. 1 that the toy will readily rise along the rod with the machine running at a speed of 8 to 10 miles per hour and will rise and fall along the rod as the speed is varied. If the velocity of the wind is greater than 8 to 10 miles per hour the tail may be suitably adjusted as to the dotted line position shown in Fig. 1, whereby the toy will rise and fall according to variations in the wind velocity. It will be understood that the wings of

the toy may be made adjustable instead of the tail and that the present disclosure is merely illustrative, and consequently various changes and modifications may be made.

5 Having thus described my invention what I claim as new and desire to secure by Letters Patent, is:—

10 The combination of a vertical rod, a sleeve slidingly mounted upon said rod and provided with collars inclined relative to the axis of said sleeve, a body portion freely

mounted upon said sleeve between said collars to permit an oscillating movement of said body on said sleeve, wings secured to said body portion, inclined relative to said sleeve, and provided with openings loosely engaging said sleeve, and a tail member connected with said body.

Signed at New York, in the county of New York, and State of New York, this 7 day of 15 October, A. D. 1921.

CHRISTIAN RUMOHR.
